UNITED STATES PATENT OFFICE.

WILLIAM H. PERRY, OF CONCORD, NEW HAMPSHIRE.

DESIGN FOR A MONUMENT.

SPECIFICATION forming part of Design No. 21,432, dated March 29, 1892.

Application filed March 3, 1892. Serial No. 423,672. Term of patent 3½ years.

To all whom it may concern:

Be it known that I, WILLIAM H. PERRY, a citizen of the United States, residing at Concord, in the county of Merrimac and State of New Hampshire, have invented and produced a certain new and original Design for Monuments, of which the following is a specification.

In order to make my design more clearly understood, I have shown in the accompanying drawing an embodiment of the same, and I will now proceed to describe the design, reference being had to the said drawing, and to the letters of reference marked thereon.

15 The leading feature of my design consists in the particular configuration of the base, the pedestal, and the shaft.

The base is shown at 1 and has four vertical sides at its top, terminating in an obtuse 20 frustum 2 of a pyramid.

25 3 is the pedestal, having four vertical sides rising from the top edge of the frustum 2 and terminating in an acute frustum of a pyramid. (Shown at 4.) One or more of the sides of the frustum 4 is ornamented by a raised tablet 5. The shaft 6 has for the main portion of its length four vertical sides and terminates at its lower end in an inverted frustum of a pyramid 7, which meets the upper 30 end of the frustum 4. The shaft 6 terminates at its upper end in a four-sided dome 8, the sides of which meet at an apex 9.

Another feature of my design consists in the ornamentation of the sides of the shaft 6, 35 said ornamentation of each side comprising the three tablets 10, 11, and 12. The tablet 10 is in relief upon the side of and near the lower end of the shaft and may have an arched upward extension 13, narrower than the main 40 part of the tablet, leaving at each side spaces 14. The tablet 11 may be in relief or designated by a surface of a different character

from the other portions and distinguished therefrom by a border-line 15, having the configuration shown. The lower end of said 45 tablet 11 corresponds with the form of the top of tablet 10, and when the latter is arched, as shown, the lower end of said tablet 11 has a concaved arch 16, partly inclosing said arch 13, and has also the downward projections 17, 50 situated in the spaces 14. At its upper end the tablet 11 has a pointed arch 18, narrower than the tablet and leaving at each side spaces 19. The tablet 12 is in relief and has at its lowerside the concaved arch 20, which receives 55 the arch 18, and has at each side downward extensions 21, which are situated in the spaces 19. The said tablet 12 has an arched top 22, situated on the face of the dome 8 and having at its base flat shoulders 23, extending 60 laterally. From the outer edges of said shoulders to the angle of the shaft the tablet 12 is bounded by a concave curve 24.

Another feature of my design consists in the ornamentation of base, pedestal, and shaft 65 by surfaces of different character.

The surfaces indicated at A, I term "rock-work," those at B "hammered work," and those at C denote "polished work." The surfaces C are flat and worked to a high polish 70 in the usual manner, the surfaces B being produced by the ordinary hammer, while the surfaces A are to be left as nearly as possible just as they are split.

What I claim is—

75 The design for a monument, substantially as shown and described herein.

In testimony whereof I affix my signature in presence of two witnesses.

WILLIAM H. PERRY.
